FIG. 1 is a front top right side perspective view of a biochemical analyzer showing our new design;
FIG. 2 is a front elevational view thereof;
FIG. 3 is a top plan elevational view thereof;
FIG. 4 is a right side elevational view thereof;
FIG. 5 is a rear elevational view thereof;
FIG. 6 is a bottom plan view thereof; and,
FIG. 7 is a perspective view thereof, with the cover in open condition.

FIG. 1

FIG. 2

FIG. 3

FIG. 4
